UNITED STATES PATENT OFFICE.

RALPH R. ROOT, OF CLEVELAND, OHIO.

ELECTRIC SIGNALING DEVICE.

1,193,926.

Specification of Letters Patent. Patented Aug. 8, 1916.

Application filed October 23, 1915. Serial No. 57,388.

To all whom it may concern:

Be it known that I, RALPH R. Root, a citizen of the United States, residing at Cleveland, in the county of Cuyahoga and State of Ohio, have invented a certain new and useful Improvement in Electric Signaling Devices, of which the following is a full, clear, and exact description.

This invention relates to electric signaling apparatus wherein a flexible diaphragm is vibrated by means of an electromagnet.

The object of the invention is to provide certain features of construction which will enable efficient operation of the horn and further provide a construction which may be readily formed up at a low cost of production.

Generally speaking, the invention comprises the elements and combinations thereof set forth in the accompanying claims.

Reference should be had to the accompanying drawings forming a part of this specification, in which—

Figure 1 is a sectional elevation of the operating mechanism for the horn and the casing which contains it; Fig. 2 is an end elevation of the horn with the casing removed; Fig. 3 is an end elevation with portions in section of the mechanism of the horn with the casing removed; Fig. 4 is a side elevation of a portion of the horn; and Fig. 5 is an elevation taken in a plane at right angles of the showing in Fig. 4.

The present horn employs a base or supporting member 1 which is provided with a central opening in which opening is fastened the amplifier or horn proper 2. This amplifier may be secured in any desired manner. The base member is saucer-shaped and provided with an annular shoulder 3. Against the shoulder 3 there lies the ring of a diaphragm 4 and upon the diaphragm there lies a portion of a supporting member 5. The outer or peripheral portion of the base 1 is folded around the edge of the diaphragm 4 and the edge of the support 5, thus holding these members together as a unitary structure which is water-tight.

The support 5 at the central portion thereof carries a cup-shaped member 6. This cup-shaped member forms the outer portion of the iron core of an electro-magnet. There is an inner portion 7 for the core which comprises a cylindrical member having an opening through the central part

thereof. The member 7 has a reduced or neck portion, as indicated at 8', and this neck portion extends through an opening formed in the bottom portion of the cup 6 and through an opening formed in the central part of the support 5. The outer end of the neck portion 8' is swaged so that the parts 6, 7 and 5 are secured to each other.

Extending transversely of the support member 5 is a member 8. This member is provided with an opening at substantially the central portion thereof and through this opening the neck 8' also extends so that this member 8 is also held in the manner just above indicated. The member 8 is provided with arms 9 and 10 which are resilient in character. These members, as will be seen by reference to Fig. 2, are leaf-like members. When lying in normal and unflexed position, the members 9 and 10 tend to extend upwardly and outwardly with respect to the member 8 which joins these arms. These arms 9 and 10 are held in the position in which they are shown in Fig. 1 by means of a transversely extending member 11. This member 11 is provided with slots 12 at its ends which are adapted to engage with the end portions of the arms 9 and 10, thus restraining and holding them in the position shown in Fig. 1. The transverse member 11 is held to the arms by imparting to the free ends of the arms 9 and 10 a slight bending, as indicated at 12'.

The transverse member 11 is resilient and has secured to it the armature 13. This armature is usually circular or in any event is of the same configuration as the configuration of the cup 6 and it will be seen that the armature 13 is in such a position as to be in line with the cup 6 and the inner core member 7. The transverse member 11 supports a transversely extending contact member 14. This contact member is separated from the transverse member 11 by means of insulating material indicated at 15. The contact member 14 is of resilient material and at its opposite ends co-operates with contact members 16 and 17. The contact member 14 is slightly flexed, as will be seen in Fig. 1, when the armature is in unattracted position as it is shown in Fig. 1. When the armature is attracted toward the core of the electro-magnet the ends of the contact member 14 wipe against the contact members 16 and 17 thus slightly prolonging the contact, but

will eventually leave the members 16 and 17 and thus interrupt the circuit flowing through the coils of the electro-magnet.

It will be noted that the construction above defined provides a double contact and break. This feature is of value in that it reduces the spark at the time of break and there is a further advantage in that if one contact becomes impaired it will not destroy the operation of the device as long as the other contact remains in operable condition.

To the diaphragm 4 there is secured a pin 4^a which extends through the central portion 7 of the electro-magnet; and this pin 15 extends slightly beyond the member 7 so that as the armature 13 is attracted it will first strike against the pin 4^a imparting a sharp blow thereto which is transmitted to the diaphragm 4.

20 For purposes of adjustment, the contact members 16 and 17 are adjustably mounted with respect to the transversely extending contact members 14. Each contact member 16 and 17 has an extension indicated at 16^a and 17^a. Each extension is provided with slots, such as indicated at 17^b and 17^c, and each extension is insulated from the arms 9 and 10 by means of insulating material such as indicated at 19 in Fig. 1. The extensions 25 for the contact members 16 and 17 are held upon the arms 9 and 10 by means of screws extending from holes in the arms 9 and 10, which screws thread into plates one of which is shown at 20 in Fig. 1, the screws extending through the slots formed in the extensions 16^a and 17^a. The plates 20 are insulated from the extensions 16^a and 17^a by a sheet of insulating material, such as indicated at 21. The slots formed in the extensions 16^a and 17^a are of sufficient size to provide plenty of clearance around the screws which hold the parts together, this clearance not only permits adjustability but prevents short-circuiting.

45 The cup member 6 is provided with an extending lip 22. This lip supports a block 23 of insulating material. The block carries terminal members 24 and 25. One of the terminal members, as 24, is secured to one of 50 the contact members, such for instance as 16. A convenient way of accomplishing this result I find by providing the extension 16^a with an arm 16^c. To this arm there is secured a conductor 26. To the terminal 25 55 is secured a conductor 27 which forms one terminal for a coil 28 which is carried within the cup member 6. The other terminal of the coil which is represented at 29 is fastened to an arm 17^a which is formed upon the extension 17^a of the contact 17. The terminals leading from a battery or source of electric current will be fastened to the terminals 24 and 25 of the signaling device. The conductors from the battery may enter 65 the casing which surrounds the horn by

means of an opening suitably formed in the horn.

The mechanism of the horn is inclosed within a cover 30. This cover is cup-shaped and at the rim of the cup is formed with an outwardly extending flange which lies against the support 5. The cover is secured by means of a yoke member 31, the legs of which are secured to the lips 22 and 22^c of the cup-shaped member 6 of the electro-magnet. The cover 30 is secured to this yoke by means of a screw 32, as indicated in Fig. 1.

Having thus described my invention, what I claim is:—

1. In an electric signaling device comprising an electric magnet, a support therefor, a pair of oppositely disposed resilient arms, a transverse flexible member engaging and holding the said resilient arms, an armature carried by the said transverse member, a conducting member extending transversely of the armature, contact members located adjacent each end of the conducting members with which the ends of the conducting members may contact, a diaphragm, and means whereby movement of the armature may be transmitted to the diaphragm.

2. In an electric signaling device comprising an electric magnet, a support therefor, a pair of oppositely disposed resilient arms, a transverse flexible member engaging and holding the said resilient arms against their outward tension, an armature carried by said transverse member, a conducting member extending transversely of the armature, adjustable contact members located adjacent each end of the conducting member with which the ends of the conducting member may contact, a diaphragm, and means whereby movement of the armature may be transmitted to the diaphragm.

3. In an electric signaling device comprising an electric magnet, a support therefor, a pair of oppositely disposed resilient arms, a transverse flexible member engaging and holding the said resilient arms, an armature carried by the said transverse member, a conducting member extending transversely of the armature, contact members adjustably carried by the said resilient arms, the said contact members co-operating with the ends of the conducting member, a diaphragm, and means whereby movement of the armature may be transmitted to the diaphragm.

4. In an electric signaling device comprising an electric magnet, a support therefor, a pair of oppositely disposed resilient arms, contact members carried by the said arms, said contact members being insulated from the said arms and adjustable thereon, a transverse flexible member engaging and holding said resilient arms against their outward tension, an armature carried by said transverse member, a conducting member

carried by the transverse member, which conducting member is insulated from the transverse member, the conducting member coöperating with the contact members, a 5 diaphragm, and means whereby movement of the armature may be transmitted to the diaphragm.

5. In an electric signaling device comprising an electric magnet, a support therefor, 10 a pair of oppositely disposed resilient arms, a contact member adjustably mounted on each arm, said contact member comprising a head portion and an extension, said extension being provided with slots, means ex- 15 tending through the slots securing the extensions of the contact members upon said arms, said contact members being insulated from the said arms, a transverse flexible member engaging and holding said resilient 20 arms, an armature carried by said transverse member, a resilient conducting member ex- tending transversely of the armature, said conducting member extending beneath the

head portions of the contact members, a diaphragm, and means whereby movement 25 of the armature may be transmitted to the diaphragm.

6. In an electric signaling device comprising a diaphragm, an electric magnet having a central opening, an armature co- 30 operating with the electric magnet, a pin ex- tending through the opening in the electric magnet, said pin coöperating with the ar- mature and diaphragm, a pair of oppositely disposed spring arms, a transverse flexible 35 member engaging and holding the said re- slient arms, said transverse member form- ing a support for the armature, a conducting member extending transversely of the ar- mature, contact members with which the op- 40 posite ends of the conducting member co- operate.

In testimony whereof, I hereunto affix my signature.

RALPH R. ROOT.
